(57) **CLAIM**

I claim the ornamental design for a modular lighting device, as shown and described.

DESCRIPTION

FIG. 1 is a perspective view of a modular lighting device showing my new design, as viewed from the top and one side.

FIG. 2 is a back elevation view of the modular lighting device of FIG. 1.

FIG. 3 is a top plan view of the modular lighting device of FIG. 1.

FIG. 4 is a front elevation view of the modular lighting device of FIG. 1.

FIG. 5 is a bottom plan view of the modular lighting device of FIG. 1; and,

FIG. 6 is a side elevation view of the modular lighting device of FIG. 1.

The details shown in broken lines illustrate portions of the modular lighting device that form no part of the claimed design.
